UNITED STATES PATENT OFFICE.

FRANK D. JOHNSTON, OF MASSILLON, OHIO.

DESIGN FOR A HOSE-CLAMP MEMBER.

SPECIFICATION forming part of Design No. 31,688, dated October 17, 1899.

Application filed August 8, 1898. Serial No. 688,117. Term of patent 14 years.

To all whom it may concern:

Be it known that I, FRANK D. JOHNSTON, a citizen of the United States, and a resident of Massillon, Stark county, Ohio, have invented and produced a new and original Design for a Hose-Clamp Member, of which the following is a specification, reference being had to the accompanying drawings, forming part thereof.

10 Figure 1 is a perspective view. Fig. 2 is a transverse section on line *a a*, Fig. 1. Fig. 3 is a section on line *x x*, Fig. 1.

As shown in the drawings, the leading or material feature of my design consists of the 15 convexo-concave section 1, having at the ends thereof the ribs or flanges 2, said ribs or flanges extended entirely across the concave face of the section 1. The ribs 2 are connected at their ends by means of the ribs 3, 20 which ribs are located at the inner edges of the member 1.

To one side of the member 1 is extended the flange 4, which flange is rounded upon its edges, and between the rounded edges is located the open recess 5. The opposite side 25 of the member 1 is provided with the hollow flanges 6, said hollow flanges being spaced a short distance one from the other, as illustrated in the drawings.

Having fully described my invention, what 30 I claim as new, and desire to secure by Letters Patent, is—

The design for a hose-clamp member, as herein shown and described.

In testimony that I claim the above I have 35 hereunto subscribed my name in the presence of two witnesses.

FRANK D. JOHNSTON.
